Primary Examiner—Alan P. Douglas*Assistant Examiner*—Lavone D. Tabor*Attorney, Agent, or Firm*—Roger S. Dybvig**[57] CLAIM**

The ornamental design for a cord guard, as shown and described.

DESCRIPTION

FIG. 1 is a top plan view of a cord guard showing my new design, the bottom plan view thereof being substantially a mirror image;

FIG. 2 is a right side elevation view thereof, the left side elevation view thereof being substantially a mirror image;

FIG. 3 is a section view thereof taken along line 3—3 of FIG. 3;

FIG. 4 is a section view thereof taken along line 4—4 of FIG. 1;

FIG. 5 is a forward end view thereof;

FIG. 6 is a section view thereof identical to FIG. 4 but on a larger scale than FIG. 4;

FIG. 7 is an enlarged, circumferential section view thereof taken along line 7—7 of FIG. 6; and,

FIG. 8 is an enlarged, circumferential section view thereof taken along line 8—8 of FIG. 6.

The broken lines in FIGS. 1 and 2 showing the portion of a cord guard connector ordinarily located within an appliance are used for illustrative purposes only and form no part of the claimed design.
